United States Patent Office

Des. 190,128
Patented Apr. 18, 1961

190,128

VEGETABLE BIN OR SIMILAR ARTICLE

Charles O. Bliss, P.O. Box 47607, Los Angeles, Calif.

Filed June 10, 1960, Ser. No. 60,909

Term of patent 14 years

(Cl. D44—1)

Fig. 4.

Fig. 5.

Fig. 6.

Fig. 7.

Fig. 1 is a top plan view of a vegetable bin or similar article, showing my new design;

Fig. 2 is a front elevational view thereof;

Fig. 3 is a rear elevational view thereof;

Fig. 4 is a bottom plan view thereof;

Fig. 5 is a bottom plan view thereof;

Fig. 6 is an end elevational view thereof, both ends having the same appearance;

Fig. 7 is a sectional view on the line 6—6 of Fig. 1;

Fig. 8 is a top elevational view, the removable end trays shown in Figs. 1, 6 and 7 being removed;

Fig. 9 is a front elevational view of the bin, with the end trays removed; and

Fig. 10 is an end elevational view of the bin, with the end trays removed, both ends of the bin having the same appearance.

I claim:

The ornamental design for a vegetable bin or similar article, substantially as shown and described.
